UNITED STATES PATENT OFFICE.

GEORGE MERRIHUE FENN, OF CHARLOTTE, MICHIGAN.

MACHINE FOR BENDING SCYTHE-SNATHS.

SPECIFICATION forming part of Letters Patent No. 707,221, dated August 19, 1902.

Application filed March 18, 1902. Serial No. 98,852. (No model.)

To all whom it may concern:

Be it known that I, GEORGE MERRIHUE FENN, a citizen of the United States, residing at Charlotte, in the county of Eaton and State 5 of Michigan, have invented a new and useful Machine for Bending Scythe-Snaths, of which the following is a specification.

This invention relates generally to wood-bending apparatus, and particularly to a machine for bending scythe-snaths.

The objects of the invention are, in a ready, simple, practical, and thoroughly-feasible manner, to prevent stretching of the fibers of the snath-blank on the outside of the bends and 15 to effect compression of the fibers on the inside thereof, to obviate splintering or breaking of the blank, to effect large saving both in time and labor in the production of the finished product, thereby greatly reducing its 20 cost of manufacture, to effect perfect uniformity of the output, and generally to simplify and improve the existing modes of manufacturing scythe-snaths.

With these and other objects in view, as 25 will appear as the nature of the invention is better understood, the same consists, generally stated, in a machine of the character specified embodying in its construction a stationary head or die, the operative face of 30 which contains all of the horizontal bends of a scythe-snath, a movable former or plunger, the operative face of which also contains all of the said bends, a vertically-reciprocating former, the operative face of which contains 35 all of the vertical bends of the snath, and a removable frame or form, the bottom of which contains all of the vertical bends and the sides all of the horizontal bends of the snath. In conjunction with the parts named there is 40 provided a flexible jacket comprising two members disposed, respectively, in front and in rear of the blank and movable therewith as the horizontal bends are being imparted thereto and operating to prevent splintering 45 or breaking of the blank, in addition to which jacket there is provided positively-operating mechanism to exert end pressure on the blank, thereby to prevent tearing or breaking of the fibers on the outside of the bends as the blank 50 is being formed.

The invention consists, further, in the novel manner of timing the operations of the two

movable formers, whereby the belly or horizontal bend of the blank shall be entirely completed and the blank moved over the form 55 that is to receive it before the former that is to impart the vertical bends shall start to operate.

With these and other objects in view, as will appear as the nature of the invention is 60 better understood, the same consists in the novel construction and combination of parts of a machine for bending scythe-snaths, as will be hereinafter fully described and claimed.

In the accompanying drawings, forming a 65 part of the specification, and in which like numerals of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof, and in these drawings—

Figure 1 is a view in perspective of a complete machine capable of carrying the procedure hereinafter described into effect. Fig. 2 is a view in vertical longitudinal section. Fig. 3 is a view in plan viewed from the top 80 of the machine. Fig. 4 is a view in horizontal section taken through the rear portion of the machine. Fig. 5 is a view in transverse section taken on the line 5 5, Fig. 3, and looking in the direction of the arrow thereon. Fig. 6 is a perspective detail view of the form or frame into which the snath-blank is forced to receive its vertical bends and in which it is held while being dried. Fig. 7 is a detail view in plan of a slightly-modified form of 90 mechanism for imparting end pressure to the snath-blank. Fig. 8 is a view in transverse section taken on the line 8 8, Fig. 7, and looking in the direction of the arrow thereon. Fig. 9 is a sectional detail view showing one 95 form of adjusting mechanism for the levers that impart end pressure to the blank.

Referring to the drawings, 1 designates generally the frame of the machine, comprising a transversely-disposed table 2, having a rearward-projecting extension 3, upon which are mounted two guides 4, between which works the plunger or former 5, the forward face of which is curved to conform to the horizontal

- bends of the snath. Connecting with the rear portion of the plunger and working in a longitudinal slot therein is one arm 6 of a toggle-lever, fulcrumed at 6^a to the plunger, 5 the other arm 7 of the lever being fulcrumed at 8 to a fixed part of the frame in rear of the plunger. The upper terminals of the arms 6 and 7 have connected with them, through the medium of a fulcrum-pin 8^a, one end of a 10 rod or bar 9, the other end of which is connected to a wrist-pin 10, connecting two gear-wheels 11, carried by a shaft 12, mounted in suitable bearings in the frame. These gear-wheels mesh with two pinions 13, carried by 15 a shaft 14, one end of which bears a gear-wheel 15 in mesh with the pinion 16, carried by one end of a shaft 17, the other end of which carries a band-pulley 18, connected by a belt with any suitable source of power. 20 While not herein shown, it being thought unnecessary so to do, it is to be understood that suitable clutch mechanism may be associated with the shaft 17, whereby the pulley may be made fast or loose with relation to 25 the shaft, as may be desired.
- It will be seen that upon motion being imparted to the pinion 16 the gear-wheels 11 will be driven, thereby drawing down the arm 9 and moving the arms 6 and 7 toward a horizontal plane, causing the plunger to move forward, the limit of its forward movement being reached when the arms 6 and 7 shall have assumed a horizontal plane, the plunger in this movement imparting the horizontal 30 or belly bend to the scythe-snath by coaction with a fixed former or head 19, disposed at the rear of the machine and, as before stated, containing all of the horizontal bends of the snath.
- 40 In the operation of imparting the horizontal bend to the blank it is essential that the blank be shielded against any tendency to splintering or breaking and at the same time that end pressure be progressively applied to 45 the butt and tap of the blank in order to effect compression thereof, and thereby obviate any tendency of the fibers on the outer side of the bend from being unduly stretched or from breaking. The means for effecting these 50 results comprise a flexible jacket consisting of two strips or bands of metal 20 and 21. The band 20 is carried by the head 19 and is held associated therewith by providing each of its ends with a rod or bar 22, which pass 55 through abutments 23, disposed near each end of the head, and carry at their extremities adjusting-nuts 24, between which and the outer sides of the abutments are disposed coiled springs 25, by which the tension of the 60 band may be regulated as desired, and to facilitate yielding of the band rollers 26 may be employed near its terminals, as clearly shown in Fig. 4. The band 21 is associated with the terminals 27 and 28 of two levers 29 65 and 30, pivotally connected with the ends of the head 19 through the medium of bolts 30^a, one of which is clearly shown in Fig. 9, the

terminals of the heads being slotted at 30^b for the reception of the levers. The band 21, which at its terminals is constructed in the same manner as the band 20, carries at that end which projects through the terminal 27 a nut 31, between which and the outer face of the said terminal is interposed a spring 32, while that end that projects through the terminal 28 has associated with it a slide-bearing 33, bearing at one end against a coiled spring 34, housed in the terminal, which is recessed for this purpose, the other terminal of the spring bearing against the wall of the recess. The outer end of the terminal of the bend 21, which projects through the bearing 33, as clearly shown in Fig. 3, carries an adjusting-nut 35, between which and the said bearing is interposed a coiled spring 36, that 80 operates to keep the band under requisite tension. The provision of the sliding bearing 33 is essential in order that the band may be forced up close against the terminal of the butt, thereby to impart the short horizontal 85 bend thereto, as clearly shown in Fig. 4, it being obvious that without the provision of the bearing 33 this could not be effected in a thoroughly practical manner without danger of kinking or breaking the band. The levers 90 29 and 30, which in effect constitute toggles, are provided for the purpose of giving progressive end pressure to the blank as the horizontal bends are being imparted thereto, and thus in a positive manner to prevent stretching of the fibers of the wood on the outside 95 of the bends. To impart the necessary outward and inward movements to the said levers in order first to move the terminals 27 and 28 of the levers 29 and 30 into engagement with the ends of the snath-blank, thus 100 to compress the same, and then to move the said terminals laterally for engagement with a fresh blank there is provided for the first movement an adjustable bar 37, carrying at 105 its inner end a head 38, having its outer face concaved, as at 39, to conform to the crest of the belly bend, and thus distribute the strain thereon to reduce danger of marring at that point, the rear portion of the 110 head being curved or rounded and being adapted when the plunger is moved to the limit of its forward movement to rest in a recess formed in the front face of the head. The rod 37 is made adjustable or extensible 115 to enable it to meet the requirements arising in bending snaths wherein the curves of the belly bend will vary, and to effect this the rod is constructed of two sections 41 and 42, and these two sections are superposed and 120 have their opposed faces serrated, as at 43, the member 42 being provided with a slot 44, through which passes a bolt 45, carried by the member 41, a nut 46 on the bolt serving 125 to hold the two members at the desired adjustment.

To adapt the levers 29 and 30 for coöperation with snath-blanks of different lengths and also to effect their proper adjustment

with relation to the other parts of the apparatus, the terminals thereof are adapted for movement to and from the terminals of the blank, and this is effected by providing the 5 terminals of the head, through which the bolts 30^a pass, with slots 46^a, the upper and lower sides of the said head-terminals on each side of the slots being serrated and engaged by serrated plates 46^b, through which 10 the bolts 30^a pass. It will be seen that by loosening the nuts of the bolts the terminals of the levers may be adjusted with relation to the ends of the blank and may be held permanently in such adjustment by clamping 15 the plates 46^b in position.

Instead of having the band 20 associated with the head the same may be associated with the terminals of the levers 29 and 30, as shown in Fig. 7, and be made to perform 20 the same functions as when disposed as shown in Figs. 3 and 4.

The free ends of the levers 29 and 30 are slotted, as at 47, to receive the upturned end 48 of a bar 49, the other end 15^a of which 25 projects upward through a recess 50 in the plunger, as clearly shown in Fig. 2, the bar 49 being longitudinally adjustable in the same manner as and for the same purpose as the rod 37, as clearly shown at 51 in Fig. 2. Now 30 as the plunger moves forward the blank by contact with the band 20 moves the latter against the head 38 and forces the rod 37 outward and the terminals 27 and 28 of the levers 29 and 30 inward, effecting thereby end 35 compression of the snath-blank, and when the plunger has reached the limit of its forward movement and has commenced to return the end 51^a of the bar 49 by coaction with the forward wall of the slot 50 of the 40 plunger moves the levers 29 and 30 toward the front of the machine, thereby projecting the terminals 27 and 28 outward. As will be noted by reference to Figs. 2 and 3, the slot 50 is considerably longer than the diameter 45 of the terminal 51^a of the bar 49, thereby permitting the immediate return of the jacket to horizontal position to receive the fresh blank. The quick return of the jacket may be effected by a spring or counterweight attached at the point where the levers 29 and 50 30 connect, which will force the levers inward and their terminals outward.

The means for imparting the vertical bends to the snath-blank comprises a former 52, the 55 under face of which contains all of the vertical bends of the snath-blank. This former is connected in any suitable manner with three rods 53, preferably by means of offsets or projections 54, through which the rods project and are held associated therewith by nuts 55. The lower ends of the rod project through a cross-piece 56 and are held rigidly associated therewith by nuts 57 and 58, bearing, respectively, against the upper and lower faces 60 of the cross-piece. The ends of the cross-piece are provided with guides 59, adapted to work on tracks 60, carried by the frame of

the machine, as clearly shown in Fig. 5. As a means for depressing the cross-piece 56, and thus force the former 52 downward, a pair of 70 toggle-levers 61 is provided, the upper members of each pair of which are pivotally connected with ears 62, secured to the under side of the frame, while the lower ends are pivotally connected with the cross-piece, as by studs 63, the joints of the levers being connected by a cross bar or bolt 64. The means for operating the toggle-levers comprises a bar 65, one end of which is connected with the bar 64 and the other end to a link 66, pivotally connected to the base of the machine. The lower end of the bar 65 is provided with a curved nose 67, designed to be engaged by the wrist-pin, thereby straightening the toggle-lever 61, depressing the cross-piece 56, 75 and through the medium of the rods 53 forcing down the former 52 and imparting the vertical bends to the blank. As a means for breaking the joints of the toggle-levers 61 a lever 68 is provided, which is pivotally connected with an upright 69 of the frame and has one end provided with a slot 70, in which works a pin 71, carried by the toggle-lever 63, the free end of the lever 68 being disposed in a recess 71^a in the under side of the plunger or former 5. It will be seen that as the plunger starts to recede the lever 68 will be forced toward the front of the machine, and thereby break the joints of the lever 61. To cause rapid return of the former 52, thus to 80 give ample time for the operator to place a fresh snath-blank in the machine, springs 72 are provided, which bear upon the base of the apparatus and against the under side of the cross-piece 56. 85

The form 73, into which the bent blank is forced, is of the usual construction and is adapted to fit in a recess disposed in front of the head 19, the said recess being at its entrance end of sufficient width to permit ready 90 insertion of the form. The space thus provided for the reception of the form would permit the butt-end of a snath-blank to drop when first placed between the jacket, the tap end resting upon the table, and to prevent 95 this the terminal 28 of the lever 29 is provided on its inner face with a projection 75, upon which the butt will rest; but as soon as the plunger moves forward to bend the blank the butt will move off from this projection, 100 so that it may subsequently be forced into the form. 105

Having thus described the different parts of the apparatus, the manner in which it operates will now be explained. The parts of 110 the machine being in the position shown in Fig. 3 and the form in the position as above described, a snath-blank is placed between the jacket members 20 and 21, and the former 5 then moves forward and presses the blank 115 against the band 20, which latter then engages with the head 38 and operates to cause the terminals 27 and 28 of the levers 29 and 30 to impart end pressure on the snath-blank, 120

the plunger by coaction with the head 19 imparting all of the horizontal bends to the blank. By the time the levers 6 and 7 of the toggle have assumed an approximately horizontal position all of the horizontal bends will have been imparted to the blank, and before the plunger 5 begins to recede the wrist-pin 12 will engage with the nose 67 of the lever 65, and thereby actuate the toggles 61 to force the former 52 downward, pushing the blank from between the jacket members and into the form 73, imparting to the blank all of the vertical bends. As soon as the former 52 resumes its normal position the form 73 is lifted out of the machine with the bent snath in it, and another form is then substituted and the operation continued as before.

It is further to be understood that while this machine is described as adapted for bending scythe-snaths it can be readily adapted for bending any irregular form by providing plungers and heads having their opposed faces of the contour desired, and as this will be readily understood detailed illustration thereof is deemed unnecessary.

It will be seen from the foregoing description that the operation of this machine is continuous and very rapid, that the output will be of uniform character, and that all danger of breaking or splintering a blank is positively eliminated.

Having thus fully described my invention, what I claim as new, and desire to secure by Letters Patent, is—

1. A machine for bending scythe-snaths, comprising a flexible jacket for inclosing opposite sides of the blank, means for imparting the horizontal bends to the blank, means for imparting progressive end pressure to the blank while the said bends are being formed, and means for imparting the vertical bends to the blank.

2. A machine for bending scythe-snaths, comprising a flexible jacket for inclosing opposite sides of the blank, means coacting therewith to impart the horizontal bends to the blank, mechanism operated by the said means for imparting end pressure to the blank while the said bends are being formed, and means for imparting vertical bends to the blank.

3. In a machine for bending scythe-snaths, the combination of means for imparting the horizontal bends to the blank, a flexible jacket for inclosing opposite sides of the blank, means coacting with the jacket to impart end pressure to the blank, and means for forcing the blank from the jacket and for imparting the vertical bends thereto.

4. In a machine for bending scythe-snaths, the combination of means for imparting the horizontal bends to a snath-blank, an adjustable flexible jacket for inclosing the opposite sides of the blank, mechanism actuated by the said means for imparting progressive end pressure to the blank, and means for forcing

the blank from the jacket and for imparting the vertical bends thereto.

5. A machine for bending scythe-snaths, comprising means for imparting the horizontal bends to the snath-blank, a jacket for inclosing the opposite sides of the blank and to be flexed by the said means, and vertically-movable means for forcing the blank from the jacket and for imparting the vertical bends thereto.

6. A machine for bending scythe-snaths, comprising an adjustable flexible jacket for inclosing opposite sides of the blank, means coacting with the jacket to impart horizontal bends to the blank, and mechanism operated by the said means for imparting end pressure to the blank while the said bends are being formed.

7. A machine for bending scythe-snaths comprising a flexible jacket for receiving the blank, a plunger for imparting the horizontal bends to the blank, means for imparting progressive end pressure to the blank while the said bends are being formed, and means for imparting the vertical bends to the blank.

8. A machine for bending scythe-snaths comprising a flexible jacket for receiving a blank, a plunger coacting therewith to impart the horizontal bends to the blank, means operated by the plunger for imparting end pressure to the blank while the said bends are being formed, and means for imparting the vertical bends to the blank.

9. A machine for bending scythe-snaths comprising a flexible jacket for inclosing opposite sides of the blank, a plunger coacting therewith to impart the horizontal bends to the blank, and means operated by the plunger for imparting end pressure to the blank while the said bends are being formed.

10. In a machine for bending scythe-snaths, the combination of a movable plunger for imparting the horizontal bends to a snath-blank, a flexible jacket to receive the blank, means coacting with the jacket to impart end pressure to the blank, and means for forcing the blank from the jacket and for imparting the vertical bends thereto.

11. In a machine for bending scythe-snaths, the combination of a plunger for imparting the horizontal bends to a snath-blank, an adjustable flexible jacket to receive the blank, means actuated by the plunger for imparting progressive end pressure to the blank, and means for forcing the blank from the jacket and for imparting the vertical bends thereto.

12. A machine for bending scythe-snaths comprising a plunger for imparting the horizontal bends to a snath-blank, a jacket to receive the blank and to be flexed by the plunger, and a vertically-movable plunger for forcing the blank from the jacket and for imparting the vertical bends thereto.

13. In a machine for bending scythe-snaths, a plunger for imparting the horizontal bends to a snath-blank, a toggle-lever associated with the plunger, continuously-operating driv-

ing mechanism operatively connected with the lever, a jacket to receive a snath-blank, a vertically-movable plunger for imparting the vertical bends to the snath-blank, and intermittently-operating mechanism connecting the latter plunger with the said driving mechanism.

14. In a machine for bending scythe-snaths, a plunger for imparting the horizontal bends to a snath-blank, continuously-operating mechanism associated therewith for imparting reciprocatory movements thereto, a blank-receiving jacket coacting with the plunger, a vertically-reciprocatory plunger for imparting the vertical bends to the blank, and intermittently-operating mechanism connecting the latter plunger with the said continuously-operating mechanism.

15. In a machine for bending scythe-snaths, a plunger for imparting the horizontal bends to a snath-blank, a jacket to receive the blank, means coacting with the jacket for imparting end pressure to the blank, a former for imparting the vertical bends to the blank and for forcing it from the jacket, means disposed in the path of travel of the jacket and actuated by the forward movement of the plunger to operate the end-pressure-imparting means, and means connecting the end-pressure-imparting means and the plunger whereby upon rearward movement of the latter to return the pressure-imparting means to its normal position.

16. In a machine for bending scythe-snaths, the combination with a flexible jacket for inclosing opposite sides of a snath-blank, of means coacting with the jacket for imparting end pressure to a contained blank.

17. In a machine for bending scythe-snaths, the combination with a flexible jacket for inclosing opposite sides of a snath-blank and having its members adjustable, of adjustable means coacting with the jacket for imparting end pressure to a contained blank.

18. In a machine for bending scythe-snaths, the combination of a horizontally-movable plunger, a flexible blank-receiving jacket disposed in advance thereof, means actuated by the plunger for imparting end pressure to the contained blank, a stationary head, a vertically-movable plunger for imparting the vertical bends to the snath-blank and for forcing it from the jacket, and a form disposed below the latter plunger to receive the blank as it is forced from the jacket.

19. A machine for bending scythe-snaths embodying in its construction, a stationary head or die, the operative face of which contains all of the horizontal bends of a scythe-snath, a movable former or plunger, the operative face of which also contains all of the said bends, a vertically-reciprocatory former, the operative face of which contains all of the vertical bends of the snath, and a removable frame or form, the bottom of which contains all of the vertical bends and its sides all of the horizontal bends of the snath.

20. A machine for bending scythe-snaths embodying in its construction a blank-receiving jacket, means coacting therewith to impart end pressure to the snath-blank, a stationary head or die, the operative face of which contains all of the horizontal bends of the snath, a movable former or plunger, the operative face of which also contains all of the said bends, a vertically-reciprocatory former, the operative face of which contains all of the vertical bends of the snath, and a removable frame or form, the bottom of which contains all of the vertical bends and its sides all of the horizontal bends of the snath.

21. In a machine for bending scythe-snaths, means for imparting the horizontal bends to the snath-blank, continuously-operating mechanism associated with said means for imparting reciprocatory movements thereto, a blank-receiving jacket coacting with the bending means, vertically-reciprocatory means for imparting the vertical bends to the blank, and intermittently-operating mechanism connecting the latter means with the continuously-operating mechanism.

22. In a machine for bending scythe-snaths, the combination with reciprocatory belly-bend-forming means and a flexible jacket for inclosing opposite sides of a snath, of end-pressure-applying mechanism, and a head connected with the said mechanism and disposed within the range of flexure of the said jacket.

23. In a machine for bending scythe-snaths, the combination with reciprocatory belly-bend-forming means and a flexible jacket for inclosing opposite sides of a snath-blank, of end-pressure-applying mechanism, and a head adjustably connected with the said mechanism, and disposed within the range of flexure of the said jacket.

24. In a machine for bending scythe-snaths, the combination with a reciprocatory belly-bend-forming member provided with a slot, and a flexible jacket for inclosing opposite sides of a snath-blank, of end-pressure-applying mechanism, a head adjustably connected with the said mechanism and disposed within the range of flexure of the said jacket to close the said mechanism on the forward movement of the said member, and a bar having one end connected with the said mechanism and its other end disposed within the slot of the said member and operating on the backward movement thereof to open the end-pressure-applying mechanism.

25. In a machine for bending scythe-snaths, the combination with the belly-bend-forming means, of end pressure-exerting mechanism comprising pivoted levers having their forward terminals formed to constitute abutments to engage the ends of the snath-blanks, and their rear terminals slotted, and a bar having one terminal disposed within the slotted ends of the levers and its other terminal operatively associated with the belly-bend-forming means.

26. In a machine for bending scythe-snaths, the combination of a stationary head and a movable plunger each having its operative face containing all of the horizontal bends of a scythe-snath, of a vertical plunger having its under face containing all of the vertical bends of a snath.
27. In a machine for bending scythe-snaths, the combination of a stationary die and a horizontally-reciprocatory plunger, each having its operative face provided with all of the horizontal bends of a scythe-snath, of a vertically-reciprocatory plunger having its under face provided with all of the vertical bends of the snath, and a removable form or frame disposed below the latter plunger, the bottom of the form having all of the vertical bends and its sides all of the horizontal bends of a snath.
28. In a machine for bending scythe-snaths, the combination with the belly-bend-forming means, of end-pressure-exerting mechanism actuated by the said means, and a flexible jacket associated with the said mechanism for inclosing opposite sides of a snath-blank.
29. In a machine for bending scythe-snaths, the combination with the belly-bend-forming means, of end-pressure-exerting mechanism actuated by the said means, and a two-membered flexible blank-receiving jacket associated with the said mechanism, one terminal of one of the members of the jacket having a slide-bearing associated therewith.
30. In a machine for bending scythe-snaths, belly-bend-forming means having toggle mechanism associated therewith, vertical-bend-forming means having toggle mechanism associated therewith, positively-driven master-wheels operatively connected with the toggle mechanism of the belly-bend-forming means, said wheels being connected by a wrist-pin, a bar having one end connected with the toggle mechanism of the vertical-bend-forming means, and its opposite end provided with a nose disposed in the path of movement of the wrist-pin, means for supporting the latter end of the bar in operative position with relation to the wrist-pin, and a lever fulcrumed to the frame of the machine and having one terminal operatively connected with the bar and its other terminal disposed in the path of movement of the belly-bend-forming means.
31. In a machine for bending scythe-snaths, belly-bend-forming means having toggle mechanism associated therewith, vertical-bend-forming means having toggle mechanism associated therewith, positively-driven master-wheels operatively connected with the first-named toggle mechanism, said wheels being connected by a wrist-pin, springs co-acting with the second-named toggle mechanism and operating normally to hold the vertical-bend-forming means normally raised, a bar having one end connected with the toggle mechanism of the vertical-bend-forming means and its opposite end provided with a nose disposed in the path of movement of the wrist-pin, means for supporting the latter end of the bar in operative position with relation to the wrist-pin, and a lever fulcrumed on the frame of the machine and having one terminal operatively connected with the bar and its other terminal disposed in the path of movement of the belly-bend-forming means.
- In testimony that I claim the foregoing as my own I have hereto affixed my signature in the presence of two witnesses.
